UNITED STATES PATENT OFFICE.

WILLIAM E. DUNN AND HARRY E. DUNN, OF HOLLAND, MICHIGAN.

CONCRETE MIXER.

Application filed February 16, 1920. Serial No. 358,815.

To all whom it may concern:

Be it known that we, WILLIAM E. DUNN and HARRY E. DUNN, respectively citizens of the United States and the Dominion of Canada, and residing at Holland, in the county of Ottawa, in the State of Michigan, have invented certain new and useful Improvements in a Concrete Mixer, of which the following is a specification.

Our invention relates to improvements in apparatus for mixing cement and aggregates for the production of concrete prior to its being used for the divers purposes in which concrete is usually employed.

One of the objects of our present invention is the provision of a concrete mixer that has the mixing compartment constructed with its bottom in a substantially horizontal plane and rotatable about a central axis, with shovels or blades positioned within said mixing compartment upon fixed brackets but disposed at divers angles of inclination to the axis of the mixing compartment and at divers angles to the walls of the mixing compartment. Another object of our invention is the provision in a concrete mixing apparatus of suitable novel instrumentalities for controlling the discharge of the aggregates or mixed elements from the mixing compartment and with the co-operation of the mixing shovels or blades to substantially clean out the mixing compartment of its mixture whenever desired. Another object is the provision of suitable means for elevating and feeding the ingredients or elements to the mixing compartment which structure is adapted to be operated automatically to dump and discharge at the proper times. In connection with the mixing structure and the elevating and feeding apparatus we have devised suitable driving mechanism which is under the control of the operator and is adapted to actuate either the one or the other of said mechanisms separately, or both of them simultaneously. We have also designed a suitable clutch mechanism in connection with our apparatus for causing the divers parts to be put into operation.

Other objects which will be obvious to others skilled in this art comprise the provision of a concrete mixer and its associated parts that is relatively simple in construction so that it may be easily assembled and operated by comparatively unskilled workmen, which is economical to operate and inexpensive to manufacture, and which is

effective in performing the divers functions for which it has been designed.

We prefer to accomplish the divers objects of our invention in substantially the manner hereinafter set forth, reference being had to the accompanying drawings which form a part of this specification, in which,

Figure 1 is a vertical elevation of our improved concrete mixer looking at it from one of the sides to disclose a portion of the elevating and feeding mechanism.

Figure 2 is a vertical elevation thereof looking at the structure at substantially right angles to Figure 1, the adjacent half of the wall of the mixing chamber being removed for clearness as well as some of the structure in front of said chamber.

Figure 3 is a perspective view of the interior of the mixing chamber showing the relative disposition of the mixing and discharging shovels.

Figure 4 is a detail fragmentary view of the elevating and feeding bucket and the means for locking the same.

Figure 5 is an enlarged detail view of one face of the clutch disk.

Figure 6 is a similar view of the opposite face thereof, and

Figure 7 is a detail view in partial section showing the manner of operating the clutch.

Figure 8 is a bottom plan of the mixing compartment.

Figure 9 is a top plan of the intermediate rectangular supporting platform detached from the legs.

In the drawings similar reference characters have been employed to designate the same parts or elements throughout the divers views, and by referring first to Figures 1 and 2 it will be observed our improved mixer is adapted to be positioned a distance above the floor so that its discharge port or hopper is in a position to feed the mixture of cement and aggregates by gravity to the top of a suitable concrete molding machine or other apparatus or locality where it is convenient to have the concrete delivered. It will be understood however that our apparatus is also well adapted for use on a ground or floor level, and the illustration herein merely typifies one of the many uses of our apparatus.

Standards 10, preferably four in number, provide a support for a platform 11 that is in a horizontal plane well above the up-

per parts of the molding machine or other apparatus below the same. Mounted upon this platform is a pair of oppositely disposed substantially A-shaped castings that provide the pieces or uprights 12 of the frame for supporting the mixing compartment, the upper portions of said pieces 12 being connected by cross-rails that consist of a pair of parallel angle strips 13. Intermediate their height the uprights 12 are connected together by a casting which comprises a pair of opposite parallel side rails 14 of angular cross-section, which are centrally provided with a connecting member 15 of a circular or annular shape and has a ball-race or groove 16 in its upper face in which anti-friction balls 17 are placed. Internally of the connecting member 15 is an angle-shaped ring 18 arranged concentrically therewith and connected thereto by webs 19 so that the ring 18 is spaced therefrom a slight distance. A cylindrical conduit 20 is movably secured to the flange of ring 18 and leads downwardly either straight, or at an angle as shown in the drawing. This conduit 20 is rotatable and provides the means for conveying the concrete and aggregates to the proper or desired place.

The mixing compartment preferably comprises a bottom 21 of circular shape, having a downturned peripheral flange 22 to which the vertical cylindrical wall 23 is secured. The bottom 21, preferably, is of inverted conical shape or inclined towards the center which is provided with a central discharge opening 24. Concentric with opening 24 is a ball-race or grooved flange 25 that alines with and is arranged in apposition with the ball-race or groove 16 in the connecting frame, whereby the mixing-compartment is supported upon the anti-friction rollers or balls, as will be understood. Outside the ball-race 25 is an annular toothed rack 26 that is engaged by a bevel pinion 27 carried upon the adjacent end of a short drive shaft 28. This drive shaft 28 is journaled in suitable bearings 29 in the adjacent A-shaped frame and extends outside said bearings where an actuating pulley 30 is secured to it, which pulley derives its motion from a belt or other suitable source of power.

The central opening 24 in the bottom of the mixing compartment is kept normally covered by a conical shaped cap 31 carried upon the lower end of a vertically reciprocating rod 32 that is journaled intermediate its ends and adapted to slide in a bearing 33 mounted upon and between the horizontal cross-rails 13. The means for moving the cap to uncover the opening comprises a lever 34 fulcrumed adjacent one end upon a short bracket 35 secured to and arising from one of the cross-rails 13. The longer end of lever 34 is raised and lowered by a

rock-shaft 36 the outer end whereof has a lateral arm 37 that is actuated or reciprocated by an operating rod or handle 38. The movable end of the shorter arm of lever 34 is bifurcated, the arms 39 whereof extend upon opposite sides of rod 32 and are pivotally connected thereto. In order to prevent the cement and aggregates from being dumped onto this bearing 34 we have provided a small conical shaped shield 40 that fits down adjacent the bearing 33 when the cap 31 is in a lowered position to cover the opening in the compartment. Carried upon the cross-sills 13, preferably over one of the A-shaped end uprights is a water tank 41 connected in any suitable manner with a water supply and provided upon its interior with any suitable or well known type of float valve for cutting off the supply of water when the tank has been filled to a predetermined point (not shown). This is for the purpose of permitting the workman or operator to simply pull a chain, rod, or the like when it is desired to supply the mixing compartment with water and upon so doing the tank 41 will discharge into the mixing compartment the desired quantity of water for the batch of cement and aggregates that have been mixed, after which the tank will immediately re-fill to its predetermined level.

In order to agitate and thoroughly mix the cement and aggregates both before and after the discharge of water into the compartment, we have provided a plurality of shovels or scoops which, in addition to performing the before-mentioned functions, as adapted when the cap 31 has uncovered the central opening in the compartment, to scoop or scrape the central opening in the compartment, to scrape or scoop the mixture or batch toward the center and cause the same to be discharged through the opening 24, and at the same time effectively scrape off the surface of the bottom. As shown in the drawings, these shovels are carried upon the lower ends of brackets 42, 43, 44, and 45 that are pendently secured to the cross-rails in any suitable manner. We have shown the brackets connected to the cross-rails by bolts 46 that pass through the latter and through longitudinally elongated slots 47 in the upper portions of the brackets in order to permit lateral and longitudinal adjustment. For the purpose of turning the aggregates over and over to secure a thorough admixture of the elements as well as to discharge the batch from the mixer after the mixing has been completed, we have placed three of the shovel blades at an angle to throw the material towards the center while one of the blades is disposed so as to direct the material from the center towards the wall of the mixer. The exact disposition of these blades is not important except that it will

be borne in mind that they should accomplish the discharge of the material from the mixer as well as the thorough mixing thereof. As seen in the drawings, we have provided upon the bracket 43 a shovel 47 that is relatively low to permit the aggregates to tumble over the same and this shovel, together with shovels 48 and 49 carried upon brackets 42 and 45, respectively, are so arranged that the aggregates are tumbled or scooped toward the center, and the shovel 50 on bracket 44 is only slightly inclined to the vertical and is disposed so as to move the mixture away from the center toward the wall of the compartment.

The means for feeding the aggregates and cement to the mixer, especially when the mixing apparatus is mounted upon an elevated platform, comprises a lift or elevator structure, the bucket whereof is raised and lowered in a suitable frame or carrier through suitable instrumentalities that are driven by the drive-shaft. Uprights 51 of angle metal are secured to the platform 11 and extend a suitable distance above the cross-rails 13 and inclined parallel guides 52 of channel beams extend from the ground or floor up to and are secured to the upper ends of the standards 51. The guides 52 have their channels facing each other, and the upper ends of the uprights and guides are connected by a cross-piece comprising a pair of channel irons 53 arranged with their backs facing each other and spaced a slight distance apart to permit of the mounting of a pair of grooved pulleys 54 and 55. A suitable frame 56 of rectangular shape is provided for carrying the bucket 57, and has small blocks 58 upon the exterior of its vertical members. These blocks fit into the facing grooves or channels of the inclined members 52 so that the frame and the bucket may be guided in their up and down movements. The bucket 57 is provided with trunnions 59 in its lower portion that fit into bearings 60 on the frame which places the center of gravity of the bucket and its contents in a plane to one side of the trunnions and toward the mixer. In order to lock the bucket in a substantially upright position, we have provided a suitable latch which is adapted to hold the bucket stationary in the frame during its elevation and to be released when the bucket and frame reach the proper level for dumping the aggregates into the mixer. This latch consists of a bell-crank, one arm 61 whereof is provided with a hook-shaped end to engage a stud 62 on the bucket. The bell-crank is pivoted at the angle formed by its arms on a bracket 63 carried by the carrier frame and the other arm 64 preferably extends downwardly and has a lateral member 65 projecting therefrom in the plane of a cam or boss 66

adjustably secured to the adjacent guide rail 65. When the bucket and frame are being elevated, the lateral member 65 comes into engagement with the cam 66 which rocks the bell-crank, which releases the latch on arm 61 from the stud 62 and the overbalancing of the bucket causes the latter to tilt and dump the aggregates into the mixer. A cable 67 is secured to the cross-piece 53 and passes down under a pulley 68 journaled in the upper member of the elevator frame and then passes up over pulleys 54 and 55 and thence down to a winding sheave or drum 69 carried on the extended end of a shaft 70 journaled in bearings in the supporting frame for the mixer. The opposite end of shaft 70 has a gear 71 mounted loosely on it that is in mesh with a pinion 72 fixedly secured to the main drive-shaft 28.

A clutch mechanism is employed to lock the gear 71 to its shaft 70, which clutch mechanism is operated by a horizontally disposed rod 73 that is reciprocated longitudinally by a hook-shaped lever or actuating arm 74 pivoted to the frame of the apparatus and one end whereof extends down with in convenient reach of the operator.

This clutch mechanism comprises a hollow drum or flange 75 made integral with or secured to the adjacent side of the gear 71. Secured to the shaft 70 by any suitable means is a disk or circular plate 76 provided with a central hub to strengthen it at its point of attachment to the shaft. Set eccentrically in the inner face of the disk is a stub or pintle 77 upon which are pivoted substantially semi-circular segments 78 of the expanding band which are of L-section and the cylindrical or flange portions opposite their pivoted ends are bent inwardly to form lugs 79 having opposing faces. The segments are retained in a normally contracted position by means of helical springs 80 passing between and secured to the adjacent ends of the respective segments. The disk 76 is bored at a point substantially diametrically opposite to the location of the stub 77 for the receipt of a short or stub-shaft 81 extending upon both sides of the disk and to the inner end of which is fixedly secured an elongated block or cam 82 the smallest diameter of which is such as to snugly fit between the inwardly bent opposing faces of the lugs 79 when the segments 78 are in normal or contracted position. On the other end of stub-shaft 81 is fixedly secured a curved or crescent-shaped lever arm 82 the movable end whereof is bored and tapped to receive a bolt 83 disposed substantially radially of the shaft 70 and the end of which bolt nearest the shaft 70 is provided with a headed end 84 and which may be secured in desired relation to the lever arm by a lock-nut 85. Surrounding

the shaft 70 and movable longitudinally thereon is a collar 86 having an inclined or conical end portion 87 which is adapted to be moved to engage the headed end 84 of 5 the bolt thereby moving or rocking the lever arm 82 and rotating the stub-shaft 81 which in turn rotates the elongated block or cam 82 and expands the semi-circular segments 78 into engagement with the inner face of 10 the flange of the drum 75 thus causing the movement of the gear 71 to be transmitted to the shaft 70.

By operating the clutch mechanism just described sufficiently hard the shaft may be 15 rotated with sufficient force to elevate the bucket with its contents, and by operating the clutch lightly so that some degree of slippage is permitted it may be employed to retain the bucket in any desired elevated 20 position or to act as a brake in permitting the descent of the bucket.

A clutch mechanism, substantially similar in all respects with that just described, is provided upon the end of the main drive-shaft 28 to connect the power pulley 30 thereto and therefore need not again be described. The drum 88 in this instance is of course a part of the pulley 30 while the disk 89 and the collar 90 are carried upon 25 and rotate with said drive-shaft 28. The lever 91 pivoted to the supporting frame is employed for moving the collar to permit its beveled portion to engage the segmental shaped lever-arm and operate the segments 30 inside the drum. Also we have provided a suitable brake mechanism for retarding the reverse rotation of shaft 70 and the lowering of the bucket which comprises a drum 92 pendently secured to rail 14 of the connecting platform so that shaft 70 passes 35 axially therethrough. A collar 93 is moved longitudinally on shaft 70 by a lateral member 94 carried on the adjacent portion of rod 73 so that said collar will cause the 40 actuation of the brake element inside the drum. When rod 73 is moved to throw the gear clutch collar 93 moves away from the brake element permitting the rotation of shaft 70, and vice versa when the gear clutch 45 is released collar 93 actuates the brake elements and slows down or stops the rotation of shaft 70, and thus controlling the movement of the bucket.

What we claim as new is:—

55 1. A concrete mixer comprising a cylindrical casing having its axis in a vertical plane, a concaved bottom therefor having a discharge port in its lowest portion; said structure adapted to be rotated upon a vertical axis, and a plurality of stationary shovels positioned in said casing adjacent said bottom disposed at divers angles to the axis of rotation of said bottom whereby the material operated upon is moved trans-

versely of the direction of rotation including upwardly from said bottom and towards the center of said bottom. 65

2. A concrete mixer comprising a cylindrical casing having its axis in a vertical plane, a bottom therefor having a discharge port in its lower portion; said structure adapted to be rotated upon a vertical axis, a plurality of stationary shovels positioned in said casing adjacent said bottom disposed at divers angles to the axis of rotation of said bottom whereby the material operated upon is moved transversely of the direction of rotation and towards said central discharge port, and a vertically movable conical shaped cap extending above said bottom and adapted to cover and uncover said discharge port and to co-operate in closed position with said shovels in turning said materials. 70

3. A concrete mixer comprising a cylindrical casing having its axis in a vertical plane, a bottom therefor having a discharge port in its lower portion; said structure adapted to be rotated upon a vertical axis, a plurality of stationary shovels positioned in said casing adjacent said bottom disposed at divers angles to the axis of rotation of said bottom whereby the material operated upon is moved transversely of the direction of rotation and towards said central discharge port, a conical shaped cap extending above said bottom and coacting with said discharge port, and means for moving said cap vertically to cover and uncover said port. 85

4. A concrete mixer comprising a cylindrical casing having its axis in a vertical plane, a conical bottom therefor having a discharge port in its lower portion; said structure adapted to be rotated upon a vertical axis, a rotatable and vertically movable cap extending above said bottom for controlling said discharge port, a plurality of stationary shovels positioned in said casing adjacent said bottom disposed at divers angles to the axis of rotation of said bottom whereby the material operated upon is moved transversely of the direction of rotation, a supporting frame in which said structure is mounted having a horizontal member extending transversely above said casing on which said shovels are pendently mounted, and means for rotating said casing and bottom. 100

5. A concrete mixing structure comprising a rotatable cylindrical casing consisting of side and bottom walls the latter whereof is provided with a central discharge opening, a conical closure for said opening extending above said bottom, fixed shovels 105 extended into said casing and positioned adjacent said bottom, said shovels inclined at divers and opposing angles to the direction 110

120

125

of rotation of said casing whereby the material being mixed is moved generally towards said conical closure and is tumbled upwardly into the strata of material above the bottom stratum.

6. In a concrete mixer comprising a suitable support, a cylindrical casing revolvably mounted thereon, a downwardly concaved bottom for said casing having a discharge port in its lower portion, a conical shaped closure for said port extending above said bottom, a vertical reciprocable spindle upon which said closure is mounted, a lever fulcrumed intermediate its ends upon said support, and means coacting with the ends of said lever and said spindle whereby the movement of said lever is transmitted to said spindle to open and close said closure.

7. In a concrete mixer comprising a suitable support, a cylindrical casing revolvably mounted thereon, a bottom for said casing having a discharge port in its lower portion, a conical shaped closure for said opening extending above said bottom, a vertical reciprocable spindle upon which said closure is mounted, a rock-shaft journaled upon said support, a lever upon said rock shaft the outer end whereof engages a projecting portion of said spindle, and means for rock-

ing said shaft.

8. A concrete mixer comprising a cylindrical casing having its axis in a vertical plane, a concaved bottom therefor having a discharge port in its lowest portion,

lateral means for rotating said structure about a vertical axis whereby said discharge port is unobstructed, a plurality of stationary shovels positioned in said casing adjacent said bottom disposed at divers angles to the axis of rotation of said bottom whereby the material operated upon is moved transversely of the direction of rotation inclining upwardly from said bottom and towards the center of said bottom.

9. A concrete mixer comprising a cylindrical casing having its axis in a vertical plane, a concaved bottom therefor having a discharge port in its lowest portion, bearings concentric with said discharge port and rotatably supporting said structure, means exterior to said bearings for rotating said structure, whereby said discharge port is unobstructed, a plurality of stationary shovels positioned in said casing adjacent said bottom disposed at divers angles to the axis of rotation of said bottom whereby the material operated upon is moved transversely of the direction of rotation inclining upwardly from said bottom and toward the center thereof.

Signed at Holland, county of Ottawa, and State of Michigan, this 9th day of February, 1920.
